UNITED STATES PATENT OFFICE.

GEORGE C. ELLERTON, OF THE UNITED STATES NAVY.

SAFETY DEVICE FOR MARINE ENGINES.

1,123,264.

Specification of Letters Patent.

Patented Jan. 5, 1915.

Application filed December 27, 1910. Serial No. 599,362.

To all whom it may concern:

Be it known that I, GEORGE C. ELLERTON, a citizen of the United States and an officer in the United States Navy, have invented 5 certain new and useful Improvements in Safety Devices for Marine Engines, of which the following is a specification.

My invention relates to a safety device for marine engines and has for its object to 10 provide a device which will prevent the engineer from making the mistake of going the wrong way, that is going ahead when the signal telegraph says "astern," and vice versa; and this object I accomplish by 15 providing a warning device such as an electric bell which rings whenever the engineer does not follow the signals which he receives.

In the drawings—Figure 1 is an elevation, the electrical connections and some of 20 the other parts being shown diagrammatically; Fig. 2 is a section view on the plane II—II of Fig. 1; Fig. 3 is a side view of the sliding contact piece; Fig. 4 is a sectional view of this contact piece on the plane 25 IV—IV of Fig. 3; Fig. 5 is a modification, parts of the device being shown diagrammatically; Fig. 6 is a side view, part of the casing being shown in section; Fig. 7 shows 30 the indicating dial of the telegraph; and Fig. 8 shows one method of insulating metal parts.

Referring more particularly to the drawings, 1 is a piece of metal secured at each 35 end to the wire that actuates the gong and pointer of the engine room telegraph, the wire 2 extending to the bridge of the vessel in the usual way. Secured to this metal piece 1 is a spring contact piece 3 which 40 may be of brass, turned up at one end, and shown in detail in Figs. 3 and 4. The contact piece 3, Fig. 1, slides under a brass strip or bar 6 which is secured by means of the screws 14, 14 which are surrounded by hard 45 rubber insulating sleeves, to any suitable support, shown as a base piece 15, of wood.

7, 8, are strips of brass secured to the base plate and arranged as shown, insulating strips 9, 10, of hard rubber being interposed 50 between the strips 7, 8, and the base plate.

11 is a binding screw for securing the wire 28 to the strip 6, and 12, 13, are binding posts for securing the wires 24 and 25 respectively to the strips 8 and 7.

55 16 is a battery connected by a wire 17 to a bell or gong 18 and thence by wire 19 to

binding post 20 which is secured to and passes through a hard rubber quadrant 49. To this quadrant are secured additional binding posts 21 and 22 which also pass 60 through the quadrant 49, the lower ends of these binding posts being arranged at such distance apart that two of them will be connected by the brass spring 23 which is operated by the handle 27 or other device 65 secured to the shaft of the reverse lever. The usual stops for maintaining the handle in the proper position are shown and marked "Ahead," "Stop," and "Astern," this portion of the device being of the usual construction. From the binding post 21 the wire 24 leads to the binding post 12, and from the binding post 22 on the quadrant 49 the wire 25 leads to the binding post 13 on the strip 7. Only one bell is shown but 75 another bell 18' can be placed on the bridge in parallel with the bell in the engine room so that both will ring at once, letting the captain or officer on the bridge know when the engineer is making a mistake in the 80 operation of the engine.

The operation of the device so far described is as follows: Assuming that a signal is received by the engineer on the telegraph to go astern. The contact spring 3 85 as shown in Fig. 1 is in the normal "stop" position until the above signal is received, when it moves up as indicated by dotted lines in Fig. 1. The engineer then moves the reverse lever to backing position, as indicated at the bottom of Fig. 1, which action corresponds to that of the signal. The current will then pass from the battery 16 through the wire 17, bell 18, wire 19, binding post 20, spring 23, binding post 21, wire 90 24, binding post 12 and brass strip 8, where the current will be interrupted because the spring contact 3 is out of contact with the bar 8. If, however, the engineer should make a mistake and put the reverse lever 95 into the "go ahead" position, then the spring 23 would be in contact with the binding posts 20 and 22 and the circuit from the binding post 22 would be through wire 25 to the binding post 13, strip 7, spring contact 100 3, bar 6, binding post 11, and wire 28 back to the other side of the battery. The bell would then ring, indicating at once to the engineer that he had made a mistake. And of course if the engineer should upon receipt of a signal to go ahead move his 105 reverse lever to the "astern" position, a like

warning would be given, as the spring contact 3 would then be in its lower position and complete the circuit.

Figs. 5, 6 and 7 show a modified form of device, Fig. 7 showing the face of an engine room mechanical telegraph without the answering handle and pointer. In Fig. 5, 51 is the sprocket or notched wheel used to ring the gong when the signal is sent on the telegraph and is actuated from the bridge by the usual wires extending around the pulley wheels 52 on the shaft 53 which carries the sprocket 51 before mentioned. Secured to the face of this sprocket is a flat circular ring 60 of brass secured to and insulated from the sprocket by coöperating rubber washers 71—72 under the screw heads (Fig. 8). The lugs by which it is secured are inwardly projected to give a clear sweep to a brush 61 which may be of spring brass, which sweeps over the ring 60. 62 is a brush which may be of spring brass, which is secured to the ring 60. 63 and 64 are brass strips secured to and insulated from the top of the box which contains the pulley or sheaves and shaft, the lugs by which they are secured being outwardly projecting to clear the brush 62. These strips are attached to the outside of the box above mentioned in such a way that they do not interfere with the working of the latch and hammer that strikes the gong, this latch and hammer not being shown as they are of the usual construction. The gong and dial, Fig. 7, fit over and conceal the parts of the apparatus just described. The brush 61 which is fixed, is curved to give it spring and is secured to the box but insulated from it by the distance blocks 65, a hard rubber washer 66 being located under the head of the screw 67 which secures the brush 61 in place. 68 is a binding post by which the wire 28 is connected to the brush.

The operation of the device is similar to that before described. Thus when a signal is sent to go astern, the sprocket 51 revolves carrying the ring 60 and the contact spring 62 with it, this spring 62 sliding over the strip 64 and making contact therewith. If the engineer makes a mistake and puts the reverse lever in the "ahead" position the current comes from the battery through the wire 28 to binding post 68 on the spring 61, thence to ring 60, brush 62, strip 64, thence through the wire 25, binding post 22, spring 23, binding post 20, wire 19, bell 18, wire 17

back to the battery 16. Thus the circuit is complete and the bell rings to indicate to the engineer that a mistake has been made. By tracing the current through the wires and various connecting devices it will be seen that when the reverse lever is in the correct position the bell cannot ring but will ring only when the lever is in the wrong position. The devices as shown are simple and compact and easily installed.

It is to be particularly noted that the engineer is warned before he can actually make a mistake in starting his engines in the wrong direction, as the reverse lever must be moved to position before the throttle valve is opened.

I claim:

The combination with an engine-room telegraph, comprising a pivoted disk carrying a peripheral contact-plate, contact points supported radially to said pivot and coöperating successively with said peripheral contact plate, said disk arranged to oscillate about said pivot and electrically connect an outer and the central radial contact points, a battery, a bell, a conductor connecting the central radial contact and bell, and a second conductor connecting the other side of the bell to one terminal of the battery, "astern" and "ahead" contacts, a "common" contact adjacent said "astern" and "ahead" contacts, said "common" contact electrically connected to the other terminal of said battery, the "astern" contact connected to one of the outer radial contact points, the "ahead" contact connected to the other outer radial contact point, a movable member arranged to successively electrically connect and disconnect the "astern" and "common" contacts and the "ahead" and "common" contacts upon moving said movable member from the "astern" to the "ahead" contacts, the electric circuit including the connections between the radial contact points and "astern" and "ahead" contacts and battery and bell remaining open whereby the bell does not ring when the telegraph signal is correctly executed, and closed whereby the bell does ring when the telegraph signal is incorrectly executed.

In testimony whereof, I affix my signature in presence of two witnesses.

GEORGE C. ELLERTON.
